(57) **CLAIM**

An ornamental design for a multipurpose handheld tool, as shown and described.

DESCRIPTION

FIG. 1 is a front perspective view of a multipurpose tool showing the tools in a retracted position, in accordance with the present invention;

FIG. 2 is a back perspective view of a multipurpose tool showing the tools in a retracted position, in accordance with the present invention;

FIG. 3 is a front plan view of a multipurpose tool showing the tools in a retracted position, in accordance with the present invention;

FIG. 4 is a back plan view of a multipurpose tool showing the tools in a retracted position, in accordance with the present invention;

FIG. 5 is a first side view of a multipurpose tool showing the tools in a retracted position, in accordance with the present invention;

FIG. 6 is a second side view of a multipurpose tool showing the tools in a retracted position, in accordance with the present invention;

FIG. 7 is a top side view of a multipurpose tool showing the tools in a retracted position, in accordance with the present invention;

FIG. 8 is a bottom side view of a multipurpose tool showing the tools in a retracted position, in accordance with the present invention;

FIG. 9 is a front perspective view of a multipurpose tool showing the tools in a deployed position, in accordance with the present invention;

FIG. 10 is a back perspective view of a multipurpose tool showing the tools in a deployed position, in accordance with the present invention;

FIG. 11 is a front plan view of a multipurpose tool showing the tools in a deployed position, in accordance with the present invention;

FIG. 12 is a back plan view of a multipurpose tool showing the tools in a deployed position, in accordance with the present invention;

FIG. 13 is a first side view of a multipurpose tool showing the tools in a deployed position, in accordance with the present invention;

FIG. 14 is a second side view of a multipurpose tool showing the tools in a deployed position, in accordance with the present invention;

FIG. 15 is a top side view of a multipurpose tool showing the tools in a deployed position, in accordance with the present invention; and,

FIG. 16 is a bottom side view of a multipurpose tool showing the tools in a deployed position, in accordance with the present invention.
